UNITED STATES PATENT OFFICE.

ALFRED F. McCOLLUM, OF BLOOMSBURG, PENNSYLVANIA, ASSIGNOR OF THREE-FIFTHS
TO JAMES MAGEE, 2d, OF BLOOMSBURG, PENNSYLVANIA.

TENSION DEVICE FOR WINDING-MACHINES.

1,333,862.

Specification of Letters Patent. Patented Mar. 16, 1920.

Original application filed October 3, 1917, Serial No. 194,612. Divided and this application filed June 28, 1918. Serial No. 242,471.

To all whom it may concern:

Be it known that I, ALFRED F. McCOLLUM, a citizen of the United States, residing in Bloomsburg, Columbia county, State of Pennsylvania, have invented Tension Devices for Winding-Machines, (being a division of my Patent No. 1,317,515, granted September 30, 1919, on my application for patent filed October 3, 1917, Serial No. 194,612,) of which the following is a specification.

One object of my invention is to provide novel means for automatically governing the tension at which yarn or thread is delivered from a supply bobbin, the arrangement of parts being relatively simple, substantial and of such a nature as not to require attention or adjustment for long periods of time.

A further object of the invention is to provide a tension regulating device which shall effectively serve as a brake to prevent drifting of the supply bobbin and which shall be of such a nature as to be easily and inexpensively applied to existing machines.

These objects and other advantageous ends I secure as hereinafter set forth, reference being had to the accompanying drawings in which;

Figures 1 and 2 are respectively a front and an end elevation of a machine embodying the novel features of my invention;

Fig. 3 is an inverted plan of part of the tension controlling means for a supply bobbin;

Fig. 4 is a vertical section on the line 4—4, Fig. 3; and

Fig. 5 is a rear elevation of a detail of the invention.

In the above drawings, 1 and 2 represent a pair of standards connected at the top by a transverse table or plate 3, from the center of which depends a bracket or hanger 4. The lower end of this latter provides bearings 9 for a pair of spindles 5 and 6, whose opposite ends are carried in bearings 7 and 8, supported by or formed as part of the two standards 1 and 2. These spindles in turn support tubes α on which is wound the yarn or thread of a pair of supply bobbins 5'. The bearings 7, 8 and 9 are so formed as to permit of the convenient insertion and removal of the spindles 5 and 6.

In order to control the tension at which the thread is drawn from each supply bob-

bin, as well as to prevent the latter from drifting, I provide a suitable governing or brake mechanism, Figs. 1, 2, 3 and 4, supported on a bar or other suitable transverse structure 10 extending between the standards or columns 1 and 2 below their bearings 7, 8 and 9. On this bar under each supply bobbin is clamped a pair of parallel bars 11, which have hinged to their rear ends a pair of brake straps or bands 12 of leather or other suitable material. The opposite ends of these bars are rigidly connected by a transverse rod 13 and serve to support a pair of rollers 14 and 15, of which the latter is merely a guide or idler. The former has projecting radially from it a rod 16, on the outer end of which is mounted a weight 17 which may be clamped at any desired distance from said roller by means of a set screw 18. This weight has projecting from its upper surface a thread guiding eye 19. Said roller 14 also has projecting radially from it a pair of staple-like eyes 20 on which is slidably mounted a relatively thin rectangular plate 21.

The front ends of the brake bands 12 have connected to them relatively thin flexible leather straps 22, preferably of the dimensions of ordinary belt lacings, which after passing around the idler or guide roll 15, pass over the outside surface of the plate 21, thence around the roller 14 and down under the same plate, their lower ends preferably having fixed to them small weights 23 which serve to keep them vertically extended. The guide eyes 20 for the straps 22 project from the roller 14 to a radial plane preferably adjacent that including the weight-carrying arm 16.

By reason of the friction between the roller 14 which is usually of metal, and said straps, which are preferably of leather, as well as by reason of the gripping action of the plate 21 on account of the inward pressure of the upper portions of the straps, said arm 16 with its weight 17 is normally maintained in or adjacent a horizontal line and acts to hold the straps under tension which causes the main straps 12 to frictionally engage and serve as brakes for the supply bobbin 5'.

Mounted on the plate 3 of the frame are a pair of winding devices whose detail construction forms no part of the present invention.

tion and which draw the yarn α^2 from the supply bobbins through the tension apparatus above described.

Under conditions of operation supply bobbins α' are mounted on the spindles 5 and 6 respectively and the latter are placed in the bearings 7, 8 and 9, as shown in Fig. 1. Thereafter the brake bands 12 are carried up from the rear end of the arm 11 and forwardly over each of said bobbins, with their flexible extensions 22 passed downwardly through the eyes 20, up around the rollers 14, and down under the automatic clamping strip 21, being so adjusted that when the machine is at rest, the weighted arm 16 is substantially horizontal. The end of the thread from the supply bobbin is then carried down through the eye 19 of the weight 17 and up to the winding mechanism.

Since the weight 17 causes the brake strips 12 to frictionally engage the thread on the supply bobbin, it is obvious that as the thread is wound on a spool said weight is first raised since said supply bobbin is held from turning, and such raising continues until the straps 22 and the bands 12 are sufficiently relieved of tension to permit the supply bobbin to rotate. Thereafter the arm 16 with the weight 17 is maintained in a "floating" condition so that it exerts an even tension on the thread. Obviously if at any time the machine should stop operation, so that the tension on the thread was relieved, there could be no possibility be continued rotation or drifting of the supply bobbin, since the weight at once acts to so turn the roller 14 as to apply tension to the straps 22 and thereby cause the main brake bands 12 to frictionally grip said bobbin.

In order to prevent the portions of the straps 12 between the supply roll and the hinge 84 which connect them to the parallel bars 11, from curving in toward said roll or outwardly therefrom so as to vary their area of contact with the latter, I preferably stiffen such portions by riveting or otherwise attaching to them metal strips 85, (Fig. 5) which in the case noted constitute parts of the hinge butts. In order to facilitate the removal of an empty spindle α and putting in place of a new supply roll, I connect the hinges 84 to their supporting arms 11 by conveniently removable pins 86 which are prevented from jarring out of place under operating conditions by arranging one arm 11 of each pair so that its pin-engaged end is higher than the corresponding part of the other arm. The hinge bodies 84 are therefore slightly inclined to the horizontal so that the hinge pins which are headed, naturally tend to remain in place.

It is particularly to be noted that the connecting bars 13 serve as stops for their re-

spective weighted arms 16, which while the thread α^2 is being wound, are drawn and held against or immediately adjacent them. Under these conditions the small weights 23 acting through the straps 22 and brake bands 12, exert a slight drag on the supply roll which equalizes the tension on the thread and regulates or tends to make more uniform the running of said roll. These small weights likewise serve to automatically take up the surplus length of the straps 22 for as the supply roll diminishes in diameter, their mass and the vibration of the machine is sufficient to cause them to draw said straps around the roll 14 with the result that if the thread breaks or the supply roll is emptied, the weighted arm 16 is in its elevated position ready to prevent further turning of said roll or spindle by dropping and causing the straps to grip the same. The idlers 15 are employed to insure that the straps 22 at all times pass to the roll 14 in the same relative positions, as otherwise the length of their surfaces in contact with said roll would vary with the amount of material on the spindle α and their angle to the gripping plate would likewise vary when the weighted arm dropped. As a result of the use of my arrangement of parts the action of the brake is rendered uniform instead of variable.

The weight 17 is made movable on the arm in order that the apparatus may be adjusted to properly perform its functions at widely different speeds, it being moved inwardly on the arm for low speeds and outwardly for higher speeds.

I claim:

1. The combination of means for supporting a supply roll; a device for winding thread from said roll; and tension means including a brake band operative on the supply roll with mechanism frictionally engaging the band and controlled by the tension of the thread for normally maintaining the band substantially inoperative and automatically taking up the slack due to the decrease in diameter of the roll.

2. The combination of means for supporting a supply roll; a device for winding thread from said roll; tension means including a brake band operative on the supply roll and mechanism controlled by the tension of the thread for varying the braking effect of said band, the same consisting of a rotatable member frictionally engaging the band; with means opposed by the tension of the thread and tending to turn said member to increase the tension on the band.

3. The combination of a supporting structure having means for carrying a supply roll; means for winding a thread from said roll; a brake band operative on the roll; a rotary member around which said band passes; with a weight tending to turn said

5 rotary member to increase the tension on said band and engaged by the thread so as to turn the rotary member to decrease the tension on the band when the tension on the thread is increased.

10 4. The combination of a supporting structure; means for carrying a supply roll thereon; means for winding the thread from said roll; a tension roll carried on said structure; a brake band having one end connected to said structure and passing over the supply roll, the other end of said band being connected to the tension roll; with a weighted arm engaged by the thread and 15 normally acting to turn the tension roll in opposition to the thread tension so as to increase the friction of the band upon the supply roll.

20 5. The combination of a supporting structure having means for carrying a supply roll; means for winding thread from said roll; a tension roll mounted on the structure and having a weighted arm tending to turn it; a staple projecting from said roll; a plate 25 movable on said staple toward and from the adjacent surface of said roll; a brake having one end connected to the supporting structure and passing around the supply roll, the second end of said band passing 30 through the staple, around the tension roll, between the latter and the plate, the weighted arm of the tension roll being engaged by the thread and raised by the tension thereof to relieve the tension exerted by the tension roll on the band.

35 6. The combination of a supporting structure; means for carrying a thread supply roll thereon; a brake band passing around said supply roll; a hinge connected to the supporting structure and having an elongated butt attached to the band for stiffening the same between the hinge and the supply roll; and means for exerting tension on the other end of said band.

40 45 7. The combination of a structure for supporting the thread supply roll; a brake band having one end connected to the supporting structure and extending around said supply roll; a roller engaged by said brake

50 band; a weighted arm connected to the roller and engaged by the thread as it passes from the supply roll; with means for automatically taking up the brake band around the roller as the supply roll decreases in diameter.

55

55 8. The combination of a structure for supporting the thread supply roll; a brake band having one end connected to the supporting structure and extending around said supply roll; a roller engaged by said brake band; a weighted arm connected to the roller and engaged by the thread as it passes from the supply roll; with means for automatically taking up the brake band as the supply roll decreases in diameter, consisting 60 of a relatively small weight on the free end of said band.

65

9. The combination of a supporting structure for a thread supply roll; a roller rotatably mounted on said structure; a weighted arm connected to said roller; a plate mounted on the roller so as to be movable toward and from the same; a brake band having one end connected to the supporting structure and the other passed over said plate, 75 around the roller and under the plate; a weight on the free end of said band; and means for winding the thread after it has passed from the supply roll into engagement with the weighted arm.

80

10. The combination of a supporting structure for a thread supply roll; a roller rotatably mounted on said structure; a weighted arm connected to said roller; a plate mounted on the roller so as to be movable toward and from the same; a brake band having one end connected to the supporting structure and the other passed over said plate, 85 around the roller and under the plate; a weight on the free end of said band; means for winding the thread after it has passed from the supply roll into engagement with the weighted arm; with a guide mounted to cause the brake band to pass to said roller always in the same relative position.
